 4 Claims. (Cl. 310—36)

ABSTRACT OF THE DISCLOSURE

An electric watch includes a mechanical resonator unit. The unit consists of two vibratory masses which are driven simultaneously in short arcs in opposite directions about a common axis. An elongated adjustment member frictionally engages a pin on one of the masses. The adjustment member may be turned, its movement occurring in a plane parallel to the planes of vibration of the masses.

The present invention relates to timekeeping devices and more particularly to an adjustment device for a mechanical torsional vibratory unit in an electric watch.

The mechanical vibratory unit described in U.S. Patent No. 2,939,971 to Holt may be applied to various frequency dependent devices. In the Holt patent two annular vibrating elements are secured to a hub by radial flat springs and are driven simultaneously in opposite rotational directions about a common axis. The assembly, when excited, is a source of low frequency energy at constant frequency. The assembly is relatively insensitive to shock and vibration.

In one application of the Holt invention to a watch, the vibration elements are discs (resonators) arranged on either side of a base plate and suspended on radially spaced flat spring members so that the discs are capable of rotary vibration in opposite directions about a common axis through a limited arc. The spring members provide a restoring force. The driving force is provided by an electromagnetic coil affixed to one disc which periodically repels a magnetic element affixed to the other disc. The discs oscillate in resonance at a low frequency. The vibratory element can supply its constant frequency information to a train of gears or to electrical counting devices by mechanical pawls or by changing an electrical circuit parameter such as inductance or capacitance.

It is the objective of the present invention to provide an inexpensive and simple means by which frequency adjustment of a vibratory assembly may be effected.

In accordance with this objective, I have provided a two-mass torsional vibratory unit having an adjustment piece or regulator. The regulator is a small weight fixed to the vibratory unit and turnable about a pivot. Turning of the regulator varies its center of gravity, which changes the mass moment of inertia of the vibrating mass, thereby adjusting the frequency of vibration.

Other objectives of the present invention will be apparent from the description of the preferred embodiment of the invention set forth below, taken in conjunction with the accompanying drawings, in which:

FIGURE 1 is a perspective view of a mechanical vibratory unit having the frequency adjusting means of the present invention; and

FIGURE 2 is an enlarged plan view of the adjustment regulator.

The mechanical vibratory unit illustrated in FIGURE 1 comprises similar resonator masses 1 and 3 positioned on either side of base plate 2. The masses are suspended by means of flat spring elements 5, a first part of which is fixed by means of pin 4 to the resonator 1, a second part of the spring is fixed to the base plate 2 and a third

2

part is fixed to resonator 3 in the same manner as the first part. These spring elements suspend resonators 1 and 3 from base plate 2 and allow limited arcuate vibratory motion of the resonators with respect to the base plate 2. The resonators are driven simultaneously in opposite directions. The springs 5 supply the torsional restoring force of the system and mechanical or magnetic means (not shown) are employed to drive the resonators in opposite directions. The constant frequency vibration thus established is used to regulate the frequency of an electrical circuit or to directly drive the gear train of a watch or clock.

The general expression for a two-disc torsional vibratory system is

$$f_n = \frac{1}{2\pi} \sqrt{\frac{K(I_1 + I_2)}{I_1 I_2}} \quad (1)$$

where f_n is the resonant or natural frequency, K is the torsional stiffness of the suspension, and I_1 is the mass moment of inertia of one disc, and I_2 is the mass moment of inertia of the other.

For simple systems where the mass moments of inertia are the same for both discs, the expression becomes

$$f_n = \frac{1}{2} \sqrt{\frac{2K}{I_2}} = \frac{1}{2} \sqrt{\frac{2K}{I}} \quad (2)$$

Since K is a constant term, the expression reduces to

$$f_n = \frac{1}{2} \sqrt{\frac{K}{I}} \quad (2)$$

It is desirable to be able to adjust the frequency of such vibrating systems to a standard frequency for time-pressures that an increase of mass moment of inertia will reduce the frequency of the system.

The mass moment of inertia I for the revolving mass can be determined from the expression

$$I = \int r^2 dM$$

where r is the radius and dM is the incremental mass. The mass moment of inertia is increased by increasing the radius at which the mass is found. Such an increase in mass moment of inertia will lower the resonant frequency of the vibrating system.

Adjustment of the natural frequency at which the vibratory system resonates is effected by means of an eccentric regulator 6 which is frictionally fitted to a pin 7 on resonator 1. Regulator 6 is adjusted by being swung about pin 7. Since the regulator is eccentric with respect to pin 7, its rotation moves its center of gravity radially to the resonator 1. Moving the adjustable regulator outwardly, toward the R on scale 8, moves its center of gravity radially outward. Such movement increases the mass moment of inertia of the resonator 1, and lowers the frequency of vibration of the system. In contrast, moving the adjustable weight 6 inwardly about pin 7, toward the A on scale 8, reduces the mass moment of inertia and raises the frequency of vibration.

The regulator 6 is shown in FIGURE 2. The bore 10 is a tight fit for the pin 7. The slot 11 allows for spring grip of bore 10 about pin 7. This construction permits the regulator 6 to be rotated about pin 7 but prevents unintentional rotation. Alternatively, lock screws or the like may be employed for greater security against such unintentional motion.

It will be apparent that modifications may be made within the scope and spirit of my invention and, accordingly, I do not wish to be limited otherwise than as indicated by the terms of the appended claims. For example, each of the two resonators 1 and 3 may each have one of the regulators 6.

I claim:

1. The combination of an adjustment device and a mechanical vibratory unit, said vibratory unit comprising two masses suspended from a base such that the said masses are capable of vibrating simultaneously in opposite directions to each other, said adjustment device comprising a regulator pivoted on one of the said masses and adapted to be fixed at different angles of its movement, the said regulator being eccentrically movable in a plane parallel to the planes of vibratory motion of the said masses, said adjustment device being an elongated member having a bore near one end and said bore frictionally engaging a pin on one of the said masses.

2. The combination as claimed in claim 1, wherein said device has a slot extending from said end to said bore to provide a spring grip on said pin.

3. The combination as claimed in claim 1, wherein each mass has an adjustment device.

4. The combination as claimed in claim 1, wherein the mass has an angular scale toward which said elongate member points to indicate the extent of adjustment.
